(57) **CLAIM**

The ornamental design for a meter for automobiles, as shown and described.

DESCRIPTION

FIG. 1 is a front view of the meter for automobiles showing my new design;

FIG. 2 is a top plan view thereof;

FIG. 3 is a right side view thereof;

FIG. 4 is a front, right perspective view thereof; and,

FIG. 5 is a front reference view showing a state of use of the meter for automobiles according to the present design.

The portions shown in broken lines form no part of the claimed design.
